UNITED STATES PATENT OFFICE.

EDWIN HENRY HUTCHINSON, OF JAMESTOWN, ARKANSAS.

SAW.

SPECIFICATION forming part of Letters Patent No. 605,577, dated June 14, 1898.

Application filed November 20, 1897. Serial No. 659,320. (No model.)

To all whom it may concern:

Be it known that I, EDWIN HENRY HUTCHINSON, residing at Jamestown, in the county of Independence and State of Arkansas, have 5 invented a new and useful Saw, of which the following is a specification.

This invention relates generally to saws, and particularly to handles therefor.

The object of the invention is to provide a 10 detachable auxiliary handle for crosscut-saws, whereby the latter may be more easily and effectively operated.

With the above object in view the invention consists of a slotted plate adapted to straddle 15 the back of the saw and provided with set-screws, by means of which it is detachably secured in position upon the saw, and a wooden handle carried by the plate.

The invention also consists in certain novel 20 features of construction and in combinations and arrangements of parts hereinafter fully described and afterward specifically pointed out in the appended claim.

In order to enable others skilled in the art 25 to which my invention most nearly appertains to make and use the same, I will now proceed to describe its construction and operation, reference being had to the accompanying drawings, forming part of this specification, in 30 which—

Figure 1 is a perspective view of a portion 35 of a crosscut-saw, showing my invention applied thereto. Fig. 2 is an elevation of the handle detached from the saw. Fig. 3 is a vertical transverse section on line 33 of Fig. 2. Fig. 4 is an elevation of a portion of the plate with the handle portion removed therefrom. Fig. 5 is a vertical transverse sectional view of a slightly-modified form of my invention.

Referring to the accompanying drawings, A indicates a metal plate provided with the vertical slot B, extending upwardly from its lower edge, thus forming legs which are adapted to 45 straddle the saw.

Set-screws C are provided for detachably securing the plate upon the saw, said screws

extending inwardly through one of the legs of the plate and adjacent each end thereof.

Formed upon the upper edge of the plate and 50 adjacent its respective edges are the rounded ears or lugs D, which are perforated in line with each other to receive the pin E, which extends therethrough and secures the wooden handle portion F in position between said 55 lugs. This handle portion is either provided with a groove upon its lower surface to receive the upper edge of the plate to prevent the turning of the handle portion, as illustrated in Fig. 3, or is made flat on its under surface 60 for the same purpose, as shown in Fig. 5.

In cutting down trees a common crosscut-saw is generally employed, two men operating the same, each man holding one of the handles thereof with one hand and with the 65 other hand engaging the back of the saw for the purpose of holding the latter in a horizontal position and the teeth thereof in engagement with the tree. The more firmly the teeth are held in engagement with the tree the better the saw cuts and the cutting operation is 70 greatly facilitated. The back edge of the saw does not present a very good surface for the hand of the operator to engage, and by the use of my handle, which may be readily attached to the saw, the latter can be much more 75 conveniently operated and the operator enabled to press the teeth thereof more firmly in contact with the tree.

Having thus fully described my invention, 80 what I claim as new, and desire to secure by Letters Patent of the United States, is—

An adjustable handle for saws consisting of a clamping-plate slotted to straddle the saw-blade and formed on its upper edge at its respective ends with ears, a cylindrical handle mounted between said ears through the medium of a pin passing therethrough, and 85 clamping-screws carried by the plate, substantially as set forth.

EDWIN HENRY HUTCHINSON.
